Louis Blum, Pittsburgh, Pa., assignor to Blumcraft of
Pittsburgh, Pittsburgh, Pa., a firm

Filed Apr. 5, 1960, Ser. No. 60,056

Term of patent 14 years

(Cl. D13—7)

FIG. 1.

FIG. 2

FIG. 3

FIG. 1 is a perspective view of a combined stairway and railing unit embodying my new design:

FIG. 2 is a front elevational view thereof, portions being broken away; and

FIG. 3 is a sectional view taken along the lines and in the direction of the arrows III-III of FIGURE 2.

The broken lines showing of the floor and walls are for illustrative purposes only.

I claim:

The ornamental design for a combined stairway and railing unit, as shown and described.
